(57) **CLAIM**

The ornamental design for a silicone face cleaning brush, as shown and described.

DESCRIPTION

FIG. 1 is a perspective view of a silicone face cleaning brush showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken-line circle shown in FIG. 7 illustrates a feature of the article of manufacture that forms no part of the claimed design.
